(57) **CLAIM**

The ornamental design for a portable distributor for storing and distributing granules, as shown and described.

DESCRIPTION

FIG. 1 shows a front perspective view of a portable distributor for storing and distributing granules, including a storage reservoir and a nozzle, embodying my new design;

FIG. 2 shows a front view of the distributor as shown in FIG. 1, wherein the storage reservoir is enlarged;

FIG. 3 shows a top view of the distributor as shown in FIG. 1; FIG. 4 shows a bottom view of the distributor as shown in FIG. 1;

FIG. 5 shows a first side view of the distributor as shown in FIG. 1;

FIG. 6 shows a second side view of the distributor as shown in FIG. 1;

FIG. 7 shows a front perspective view of the nozzle portion of the distributor as shown in FIGS. 1-6;

FIG. 8 shows a front view of the nozzle as shown in FIG. 7; FIG. 9 shows a top view of the nozzle as shown in FIG. 7;

FIG. 10 shows a bottom view of the nozzle as shown in FIG. 7;

FIG. 11 shows a first side view of the nozzle as shown in FIG. 7; and,

FIG. 12 shows a second side view of the nozzle as shown in FIG. 7.

The drawings of FIGS. 7-12 are shown separated for ease of illustration.
